UNITED STATES PATENT OFFICE.

GEORGE N. HEIN, OF SAN FRANCISCO, CALIFORNIA.

HYPODERMIC SYRINGE.

Application filed May 16, 1924. Serial No. 713,754.

To all whom it may concern:

Be it known that I, GEORGE N. HEIN, a citizen of the United States, residing at the city and county of San Francisco and State of California, have invented certain new and useful Improvements in Hypodermic Syringes, of which the following is a specification.

Hypodermic syringes are either filled 10 through the ends thereof or by inserting ampul charges therein after the pistons have been withdrawn therefrom or the needle caps removed. In filling a hypodermic syringe from the end after the piston has been withdrawn therefrom necessitates that the operator first withdraw the piston, deposit the same and then pour into the open end of the barrel the fluid to be administered, then reinsert the piston and continue with the 15 operation. This is an exceedingly long drawn out operation and oftentimes requires that the piston be resterilized. These objections are also true in the use of ampuls as at present practiced, and it is to overcome 20 these objections that the present syringe has been designed.

One of the principal objects of this syringe is to provide a means whereby the liquid to be administered can be deposited 30 in the barrel without entirely withdrawing the piston from the barrel, thus overcoming the piston becoming contaminated when requiring the same to be deposited on an unsterilized surface, and enabling the administering of the charge immediately after depositing in the syringe barrel.

A further object is to provide a wall structure for the filling opening to overcome injuring the fluid seal packing provided at 40 the end of the piston. Further objects are to provide a novel form of fluid seal packing element and a novel form of releasable retaining device for holding the same within a recess in the end of the piston. Another object is to provide a wall engaging 45 flange associated with the liquid seal member, and to so form the same that a number of extremely flexible wall engaging edges are provided.

With the above mentioned and other objects in view, the invention consists in the novel construction and combination of parts hereinafter described, illustrated in the accompanying drawings, and set forth in the 55 claims hereto appended, it being understood that various changes in the form, propor-

tion, size and minor details of construction within the scope of the claims may be resorted to without departing from the spirit or sacrificing any of the advantages of the 60 invention.

To more fully comprehend the invention reference is directed to the accompanying drawings, wherein

Figure 1 is a view in elevation partly in 65 section of the improved embodiment of my invention.

Figure 2 is a view in sectional detail taken on line 2—2 of Figure 1 with the piston raised within the barrel, illustrating the 70 formation of the walls of the filling opening and the construction of the liquid seal in the lower end of the piston.

Figure 3 is a view in elevation of the liquid seal member. 75

Figure 4 is a sectional view on line 3—3 of Figure 1.

Figure 5 is a sectional view on line 4—4 of Figure 2.

In the drawings wherein like characters 80 of reference designate corresponding parts, 1 indicates a tubular barrel open at one end as at 2 and carrying at its opposite end a detachable coupling 3 which serves to mount a hypodermic needle and base 4 of the accepted type thereto. The end wall of the barrel 1 is inwardly bevelled as at 5 to facilitate the entrance of the lower end of the piston 6 of a diameter to snugly fit the interior diameter of the tubular barrel 1. 90 The plunger is provided with an operating handle 7 and is adapted for reciprocating movement longitudinally within the barrel 1. The barrel near its upper open end is formed with finger grips 8 and within its 95 wall a short distance below its upper end 2 is provided with a filling opening 9, the peripheral walls of which are downwardly and inwardly bevelled or rounded as at 10 to afford a relatively smooth surface on the 100 interior of the barrel 1. The end of the piston 6 inserted in the barrel is provided with an auxiliary chamber 11 extending a distance longitudinally thereof for the reception of a packing member 12. The inner 105 end of the chamber opens laterally as at 13 through the side wall of the piston 6 at a point removed from its end, and the chamber wall adjacent said opening 13 is inwardly turned as at 14 providing an engaging 110 surface. The packing member consists of a core 15 preferably of metal, flanged at one

end as at 16, the latter being provided with perforations 17, through which the material forming the covering may pass during the formation of the packing. The opposite end of the core is formed with a contracted neck 17', and beyond the same there is provided an enlargement 18 affording an annular shoulder 19. The elastic covering on said core is preferably of rubber and comprises a head 19 of a diameter to normally snugly engage the inner walls of the barrel 1, the head being provided with a raised portion 20, which, when compressed against the end of the core supplies material for spreading the end of the covering. A skirt 21 extends over the side walls of the core 15 and tightly engages the core, the skirt terminating short of the portion 17'. Between the head and skirt is formed an annular flange, the inner surface of which rests on the end wall 22 of the piston, and the periphery of the flange is formed with a circumferential concave groove 23 providing the flexible lips 24 for engaging the inner surface of the barrel.

The packing when in position in the piston chamber may be removed therefrom by the operator while grasping the plunger after the same is removed from the barrel, and with the thumb of the same hand inserted into the opening 13, exert inward pressure on the portion 18 to compress the skirt 21 against the lateral centering wall 25 to remove the flange 14 from the rear of the flange 19'. The operator then exerts lineal pressure on the member 18, and this forces the packing from the packing chamber 11. When a new packing is desired, the operator may select a suitable packing while the same is in the sterilizing receptacle, maneuvered until it is standing upright, insert the piston thereover, continue the downward pressure until the flange 14 passes rearwardly of flange 19', thus the packing can be renewed without the operator touching the sterilized packing. This is quite essential in devices of this type.

The pressure on the head 20 which tends to spread the same also forces the lips 24 into engagement with the barrel wall of the formation of the concave peripheral recess which insures a fluid tight seal between the peripheral lips 24 and the barrel wall regardless of which direction the piston is reciprocated therein.

Having thus described my invention what I claim as new and desire to protect by Letters Patent of the United States is:—

1. A hypodermic syringe including a tubular syringe barrel open at one end for the reception of a piston, a piston reciprocably mounted therein and provided with a chamber at one end opening at its inner end laterally through the side wall of the piston, an elastic packing member overlying the per-

iphery at the end of the piston with a portion received within the chamber, and means at the inner end of the packing for engaging the wall of the chamber through a lateral movement to establish a releasable holding contact therewith. 70

2. A hypodermic syringe including a tubular syringe barrel open at one end for the reception of a piston, a piston reciprocably mounted therein and provided with a chamber at one end opening at its inner end laterally through the side wall of the piston, an elastic packing member detachably secured to the end of the piston and including a body for reception within the chamber, a head for resting on the piston end wall, and a retaining flange for engaging with the chamber wall for establishing releasable holding contact therewith. 75

3. A hypodermic syringe including a tubular syringe barrel open at one end for the reception of a piston, a piston reciprocably mounted therein and provided with a chamber at one end opening at its inner end laterally through the side wall of the piston, an elastic packing member detachably secured to the end of the piston and including a substantially conical body for reception within the chamber, a head for resting on the piston end wall, and a retaining flange for engaging with the chamber wall for establishing releasable holding contact therewith. 80

4. A hypodermic syringe including a tubular syringe barrel open at one end for the reception of a piston, a piston reciprocably mounted therein and provided with a chamber at one end opening at its inner end laterally through the side wall of the piston, an elastic packing member reciprocable within the end of the piston and provided with a laterally extending flanged portion at its inner end, the wall at the side of said lateral chamber opening being formed to engage said flange and retain the packing member in position. 100

5. A hypodermic syringe including a tubular syringe barrel open at one end for the reception of a piston, a piston reciprocably mounted therein and provided with a chamber at one end opening at its inner end laterally through the side wall of the piston, an elastic packing member reciprocable within the end of the piston, means for detachably retaining the packing in position, said means being releasable on lateral movement being imparted to the end of the packing member through said lateral piston opening. 115

6. A hypodermic syringe including a tubular syringe barrel open at one end, a piston reciprocably mounted therein, a packing detachably carried at the end thereof, and including an elongated core of general convex configuration flanged at its head end and flanged adjacent to its other end, a flexi- 120

ble packing material covering the head end and the part of the side walls of the core and snugly fitting the same, said flexible packing being formed at its head end with an 5 annular flange provided with a circumferential concave groove of a radius to intersect the opposite edges of the flange, the full area of the end of said packing being exposed to the pressure within the barrel.

10 7. A hypodermic syringe including a tubular barrel open at one end for the reception of a piston, a piston mounted to recip-

rocate therein and provided with a sealing member for engaging the barrel wall, the syringe barrel inwardly from its open end 15 being provided with a filling opening, triangular in plan, with its base substantially parallel with the open end of the barrel and the walls thereof bevelled inwardly and downwardly from the opening, and grip 20 members associated with the barrel.

In testimony whereof I have signed my name to this specification.

GEORGE N. HEIN.
